UNITED STATES PATENT OFFICE.

EDWIN R. FELLOWS, OF SPRINGFIELD, VERMONT, ASSIGNOR TO THE FELLOWS GEAR SHAPER COMPANY, OF SPRINGFIELD, VERMONT, A CORPORATION OF VERMONT.

WORK-SETTING MEANS FOR GEAR-GENERATING MACHINES.

Application filed January 27, 1923. Serial No. 615,315.

The present invention relates to machines for finishing gears to exact size, and at the same time generating their tooth face curves accurately to predetermined forms, by a suitable cutting action simultaneously with relative generative travel between the work piece or gear blank and the cutting tool. Ordinarily and preferably the cutting action for purposes of the sort here indicated is that of grinding, and the preferred cutting tool is a grinding wheel.

I have embodied the improvements constituting the present invention in a machine equipped for performing that sort of action with a grinding wheel, and have illustrated a machine having such a grinding wheel as a practical embodiment of the invention shown in the drawings accompanying this specification, wherefore, in the following description I will generally refer to the cutting action of the machine as a grinding action, and to the cutting tool as a grinding wheel, but without intending to limit the scope in which I claim protection to this particular class of machine alone. Indeed, the principles of the invention, and even the specific embodiment thereof here shown, are not limited as to their utility to use with a grinding wheel only, but may be combined with machines having other specific kinds and types of working tool. Hence the descriptive designations of the tool and of the cutting action contained in this specification may be considered as typical of any cutting means and action which may be applied to the use and purpose of finishing previously roughed or shaped gears and other more or less similar and analogous machine elements and articles. The main fact is that the machine is provided to finish accurately previously formed gears, et cetera, and that, so far as the present invention is concerned, any machine capable of serving that end and with which the particular new features of the present invention may be used, is within the scope of the protection which I seek, so far as that protection involves the combination of such a machine with said novel features.

The improved or new steps comprised in this invention concern the setting and adjustment of the work, and the control of the operation of the machine, in order that the correct amounts of material will be removed in the final cutting operation to bring all

the work pieces of the same lot to the same finished dimensions and form, whatever these amounts may be, within practicable operating limits, in spite of specific errors and variations in the individual rough work pieces; and that these results may be effected quickly, with economy of time and elimination of unnecessary movements.

The means for the accomplishment of these objects, which comprise the substance of the invention, include provisions for quickly setting and accurately adjusting the work piece initially; means for adjustably limiting the amount of the feed to be given by the automatic action to the work piece or the cutting tool, one relatively to the other, in connection with means for timing the operations of cutting and feeding the work; and provisions for putting the operation of the machine under or out of the control of such timing means.

The principles and nature of the invention, in one concrete embodiment thereof, are explained and described in the following specification with reference to the drawings of a particular machine containing such an embodiment.

Figure 1 of such drawings shows a side elevation of the machine.

Figure 2 shows an elevation on a somewhat larger scale of a fragment of the opposite side of the machine from that shown in Figure 1.

Figure 3 is a longitudinal vertical section of a part of the machine taken on line 3—3 of Figure 4.

Figure 4 is a vertical cross section of the machine on line 4—4 of Figures 1 and 3.

Figure 5 is a fragmentary elevation showing the mechanism for controlling the timing means; the parts thereof being in a different relation from that in which the same mechanism is shown in Figure 1.

Figure 6 is a plan of the mechanism shown in Figure 5.

Figure 7 is a horizontal section of a part of the timing mechanism taken on line 7—7 of Figures 1 and 5.

Figure 8 is a cross section of the same mechanism on line 8—8 of Figures 1 and 7.

Figure 9 is a sectional view of a part of the work feeding mechanism.

Figure 10 is a cross section of the latter mechanism on line 10—10 of Figure 9.

Figure 11 is a view of the same parts

shown in Figure 10 as seen from the view point of that figure, but representing the parts in a different position.

Figure 12 is a plan view of a part of the means for initially setting the work.

Figure 13 is a plan of another part of the same means containing a gage on a different part of the machine.

Figure 14 is a section on line 14—14 of Figure 13.

Figure 15 is a cross section on line 15—15 of Figure 3, showing a detail of mechanism.

Like reference characters designate the same parts wherever they occur in all the figures.

The machine here represented is designed for finishing previously shaped spur gears by a grinding operation, and is generally, except for the parts and features novel with the present invention, substantially the same as the machine disclosed in my prior application for Letters Patent of the United States Serial No. 595,304 filed October 18, 1922, and entitled "Automatic gear generating machine." It also contains many of the characteristic features shown in my preceding application for Letters Patent of the United States Serial No. 578,288 filed July 29, 1922, and entitled "Gear grinding machine." Only so much of the machine as is necessary to an explanation of the present invention is shown and described in this specification, and for explanation of details not herein shown attention is directed to the said prior applications.

The base 1 of the machine is provided with an inclined guideway 2 on which is supported a sliding work carriage or work slide 3. A work spindle 4 (Figure 2) is 40 rotatably mounted in said carriage or slide and projects to one side of the machine, where it supports a work piece 5, a gear blank, in operative relation to a grinding wheel 6. At the opposite side of the machine from the work piece, there are rigidly connected a gear wheel or segment 7 and an element 8 which I call a "former" (Figure 1). The former has a curved face 9 which bears against the end face 10 of a 50 complementary abutment 11 which I call a "former abutment." A combination of rotation about its axis and of translation perpendicular to its axis and parallel to the guideway 2 is given to the work piece, whereby the latter is caused to roll past the grinding wheel, and the character of the 55 rolling movement of the work is determined by the form of the faces 9 and 10 of the former and abutment, respectively. The former is removable and interchangeable with others having specifically different lengths, locations, or forms of the face 9 to be used with specifically different gear blanks. Normally the abutment is stationary, having no other motions than the ad-

justments presently described, and its end face 10 has the relation to the former 9 of a rack tooth face to that of a complementary gear tooth face.

Of the grinding wheel the face 12, in a 70 plane perpendicular to its axis, is the part which acts on the work, and its relation to the teeth of the gear blank is that of a rack tooth face at the opposite side of a tooth space from the tooth to which the abutment 75 11 corresponds.

A cam 13 shown in dotted lines in Figure 1, and also shown in Figure 3, imparts movement to the work spindle and former through the medium of a bell crank lever 14, 80 a second lever 15, and a rack bar 16. The lever 14 has two arms, one of which carries a roll 17 bearing on the cam 13 and the other arm 18 of which bears on a roll 19 carried by the lever 15. The rack bar 16 is 85 pivoted to the lever 15 and has teeth which mesh with the gear 7. Thus when the rising part of the cam passes the roll 17, the gear 7 and former 8 are turned in anti-clockwise rotation, as seen in Figure 1, and the pull of the rack bar combined with the reaction of the former against its abutment 11 causes the work carriage to be moved upward and to the left (Figure 1—95 to the right, Figure 2).

The rotary motion given to the work spindle is that permitted to the former relatively to the abutment; and the compound movement of rotation and translation, both of the former to the abutment and of the 100 work piece to the grinding wheel, is equivalent to that of a gear wheel rolling in mesh with a rack. Thus the teeth of the gear blank are generated accurately to a 105 prescribed form, controlled by the faces of the former and its abutment, at the same time that they are cut away to required size by the action of the grinding wheel. Cutting takes place mainly on the upward 110 travel of the work; and at the end of the downward travel, which is effected by gravity, with aid from a spring if desired, the work is indexed in order to bring another tooth into position to be cut on the next upward travel. Operative means for connecting the former to the work spindle and for indexing the work, as well as means for mounting and adjusting the grinding wheel, and the relation of the grinding wheel in 115 all aspects, are fully illustrated in my prior application Serial No. 578,288 aforesaid.

In order to remove all of the stock necessary to bring the work to finished size, several successive cuts on each tooth are required. I prefer to feed the work piece for each next deeper cut after a preceding series of cuts of equal depth have been taken on all of the teeth. Feeding of the work is effected by turning the work spindle slightly about its axis before beginning a 125 sub-

sequent series of cuts, and this rotational movement is effected by adjustment of the abutment. For this purpose the abutment is secured to a slide 20 shown by dotted lines in Figure 1 which is movably mounted in a holder 21 and constrained to travel in a path other than parallel with its active face 10. In this machine the path of such movement is vertical and the face 10 is inclined. Hence upward movement of the slide causes the face of the abutment to act in the manner of a wedge on the former and thus to turn the work piece so that the tooth of the work piece which is next in position to be ground is advanced toward the face of the grinding wheel. Such movement is given to the slide 20 by means of a cam or wedge 22, (shown by dotted lines in Figure 1 and shown in fuller detail in Figure 9), on which the slide 20 rests, through a foot-piece 23 of the latter which projects through a sleeve in the bottom of the holder 21.

As shown in Figure 9 the wedge cam 22 is integral with a bar 24 having a screw-threaded end 25 on which is mounted a nut 26. This nut is rigidly connected with a ratchet wheel 27 at one end and with a stud or stem 28 at the other end on which a wrench may be applied. Bar 24 has a bearing in a fixed part 29 of the machine frame, passing through a bushing 30 which is rotatably held in said part and is adapted to be clamped by a binding screw 31. On one end of this bushing is mounted an abutment or back stop 32 for a pin or equivalent complementary stop 33 on the nut 26. A spring 34 surrounds bar 24 and is confined between the frame member 29 and a shoulder 35 on the bar. A sleeve 36 surrounds the nut rotatably and has a lug 37 forming a pawl carrier, on which is pivoted a pawl 38 coacting with the ratchet 27. When the sleeve 36 is oscillated the pawl rotates ratchet wheel 27 intermittently in the direction for drawing the wedge cam 22 to the right and thereby raising the abutment-carrying slide. The pawl may be disengaged from the ratchet and the nut turned in the opposite direction by hand to reset the abutment; the spring 34 then moving the wedge cam to the left and the abutment-holding slide then descending.

The pawl carrier is formed in part as a gear segment 39 meshing with a rack bar 40 (Figure 4) which is adapted to slide endwise in a guideway 41 to effect the automatic work feeding motion.

Work feeding movements are so effected in alternation with successive series of tooth grinding operations under control of a timing mechanism. That is, the mechanism which rolls the work piece past the grinding wheel is operated a number of times, enough to grind all of the teeth of the gear blank

in turn. Then the feeding mechanism is operated to advance the work piece for the next series of cuts; the work driving mechanism is again operated to perform a series of cuts, and so on until the final series of cuts is taken, and the machine is stopped. I will now explain the timing mechanism which controls the sequence of these different alternating actions, and in connection therewith I will complete the description of the automatic work feeding mechanism.

Referring now to Figures 1 and 3, the main shaft 42 of the machine, on which is mounted a driving belt pulley 43, passes through a sleeve 44, in which its inner end is supported by a bearing 45, and into an adjoining sleeve 46. These sleeves are rotatably supported in alinement within a cylindrical part 47 of the base. At their adjacent ends the sleeves are formed with internal sun gears 48 and 49, respectively, with which meshes a planet pinion 50; or a connected pair of planet pinions, mounted on an eccentric stud 51 carried by the main shaft. The gear ratios between the planet pinion and the respective sun gears are different, wherefore when either sun gear is held stationary, the other is rotated at slow speed. On the outer end of the sleeve 44 having the sun gear 48, is formed or secured the cam 13, previously described as the impeller for the work driving mechanism.

Coaxially secured to the sleeve 46 are gear 52 and a shaft 53. Gear 52 drives a complementary gear on a shaft 54 (Figure 4). On shaft 54 are mounted a number of cams. The only one which is material to the present invention is a cam 55 which I call the primary work feeding cam. This cam is adapted to oscillate an arm 56 on a sleeve 57 which loosely surrounds the shaft 53. Sleeve 57 carries a gear segment 58 in mesh with a complementary gear segment 59 connected with a pawl carrier 60 which carries a pawl 61 arranged to drive a ratchet 62; such ratchet in this machine having five teeth and thereby adapted to be turned through a complete revolution by five impulses of the pawl.

The ratchet 62 is integral, or otherwise rigidly connected (Figs. 3 and 7), with a timing cam 63 and with a sleeve 64 mounted to rotate on a pivot stud 65, and on which the pawl carrier 60 is rotatably mounted. A gear or worm wheel 66 is keyed to the sleeve 64, and has a hub on which is rotatably mounted a gear 67 in mesh with a pinion 68 (Fig. 8). Said pinion is mounted on a shaft 69 which has a bearing in the base of the machine and projects to the outer side of said base and is formed with a square end 70 to receive a wrench; or may be in any other manner equipped with means for manual rotation.

The hub of gear wheel 66 is provided with ratchet teeth 71 adapted to engage a pawl 72 carried by the gear 67 and to rotate the latter gear whenever the wheel 66 is rotated; but the gear 67 can be manually turned in the same direction when the hub of wheel 66 stands still, the pawl then slipping over the ratchet teeth. On the outer face of the gear 67 are secured a number of detachable cam segments 73 (shown in Figures 4 and 7), the function of which is to reciprocate the rack 40 whenever gear 66 is turned. These cam segments when all in place form a complete cam of five lobes; and they are made detachable in order that segments having greater or less lift, or no lift, may be substituted for one another. It will be noted in Figure 4 that these cam segments have no rise whatever in half of their angular length, and that their whole rise is limited to the remaining half. This construction is provided to permit alternate steps of the cam being taken without affecting the work feeding mechanism and to cause the intermediate steps only of the cam to operate this mechanism. I call this cam the secondary work feeding cam.

Returning to Figure 8, there is shown in mesh with the worm wheel 66 a worm 74 on a shaft 75 which rotates in a fixed bearing and carries, at the outer side of the base, a ratchet wheel 76, shown also in Figure 1. A pawl 77 drives the ratchet 76 step by step and is operated to that end by the work driving mechanism through a link 78 connected to an arm of the work driving lever 14, a bell crank lever having an arm 79 connected to link 78, and a second arm 80, a link 81 connected to the latter arm, and a pawl carrier 82 mounted to oscillate about the shaft 75 and on which the pawl is mounted. The ratchet wheel 76 is interchangeable with others and pawl 77 is adjustable on the carrier 82 accordingly, and the connection of link 81 with arm 80 is adjustable toward and away from the fulcrum of said arm in order to adjust the machine to work on gear blanks of different diameters and pitches.

Whether the work driving mechanism or the primary work feed cam 55 is put in operation depends on whether, respectively, the sleeve 46 or the sleeve 44 is withheld from rotation and the other sleeve left free to turn. Alternate arrest of one sleeve and release of the other is effected by mechanism under the control of the timing cam 63 and studs 83 projecting from the face of said cam. On the sleeve 44 are abutments 84 (Figs. 3 and 15) coacting with a stop pawl 85, while on the sleeve 46 are similar but oppositely directed abutments 86 with which coacts a stop pawl 87. These stop pawls are both mounted on a rock-shaft 88 and extend toward respectively opposite sides of

the axis of the sleeves, with such an angular spacing that, when said shaft is rocked in one direction, the stop pawl 85 is placed in the path of the abutment 84 and the stop pawl 87 is moved out of the way of the 70 abutment 86, and vice versa.

On the rock shaft 88 is an operating arm 89 connected to a shift bar 90 which, when moved upward, releases sleeve 44 and arrests sleeve 46, and when moved downward 75 effects the reverse condition. This shift bar is controlled by the timing cam 63 and its studs in a manner fully explained in my prior application Serial No. 595,304. For the present purpose it is sufficient to say 80 that with each step in the rotation of the timing cam a shift of the bar takes place in one direction or the other. In the present machine each of such steps amounts to one-tenth of a turn, although machines may be 85 built in which the effects described are obtained in a different number of steps. It is to be noted, however, that the angular extent of each rise on the secondary work feeding cam 73 is comprised within a single rotational step of the timing cam, while between the successive rises of the cam 73 are dwells 90 fully as long angularly as the intermediate steps of the timing cam.

It will now be understood that when the 95 work driving mechanism is in operation, the timing cam is slowly given one of its steps of rotation by a succession of steps of the pawl and ratchet 77, 76 and gearing 74, 66, while grinding cuts are being taken in succession on the several teeth of the work; a dwell in the secondary work feeding cam 73 then passing under the rack 40. When this step of cam 73 is completed the timing cam shifts the relation of the holding pawls 85, 87, the cam sleeve 44 is arrested and sleeve 46 left free to turn. The latter then drives the primary work feed cam 55, and said cam, through arm 56, gear segments 58, 59, and pawl and ratchet 61, 62, advances the 100 secondary work feed cam 73 while a rise thereof passes under the rack 40 and the latter is caused to turn the work feed nut 26, by means of the pawl and ratchet 38, 27, 105 110 115 120 125 130 135 140 145 150 155 160 165 170 175 180 185 190 195 200 ing mechanism is in operation, the steps then given to the secondary cam 73 cause the rises of said cam to pass under the rack bar and displace the latter. The amount of stock removed on each successive cut is determined by the height of the cam rise which previously operated the feed mechanism. By changing the segments of cam 73 the length of each step of the feed may be varied and made of any length desired, including zero length, or not feed.

When the final cut has been finished the machine is stopped by shifting the driving belt from a pulley fast on the main shaft 15 to an adjacent pulley loose on said shaft. This shifting of the belt is accomplished under the control of the timing mechanism by the following means:—A belt shifter 92 (Figure 4) engages the driving belt 93 and 20 is adapted to be moved back and forth by a horizontal endwise-movable rod 94 (Figure 1). This rod passes through a guide lug 95 on the frame of the machine and carries a collar 96 between which and said lug is confined a spring 97 under tension constantly tending to move the shifter from the fast pulley to the loose pulley. A head or knob 98 is secured to rod 94 and may be used for 25 manually shifting the belt to start the machine. When the belt shifter is in the position beside the fast pulley, a second collar 99 on rod 94 is carried beyond and interlocked with a latch 100 (Figures 1 and 4) which is held up in locking position by a 30 spring-pressed plunger 101 and is provided with a tail 102 which extends into the path of a stud or equivalent projection 103 on the hub of the gear 67. The projection 103 is so positioned that, when the cycle of the machine ends, it has arrived at the point where it displaces latch 100 and releases the rod 94.

This machine is intended to finish to exact size and form gears and other articles which have been previously shaped to an approximate form and dimensions somewhat larger than the finished size. Owing to the inevitable variations in the commercial work produced by the machines used for first shaping these articles, there is some variation between the pieces intended to be the same as to the thickness of their teeth; hence accuracy in the finished product of this machine is dependent upon the initial correct setting of the work and the removal of the right amount of material from the faces of the teeth or other projections which have to be ground. In initially setting the work the latter must be given a correct angular relation to the former, since the angular distance between the face of the former and the face of the tooth on the gear first to be brought to the grinding wheel determines the amount of stock which will be removed on the next cut. Once the work is secured to the spindle 45 all the teeth will be ground to the same thickness with respect to an assumed center line of each tooth. For so setting the work, I have provided a locating member which causes the slide or carriage to occupy a given position on the base, and a gage member 50 secured adjustably to the work slide or carriage, but made fast thereon when in use. The use of both of these adjusting devices, or their equivalents, is practically necessary on account of the different positions which the former occupies angularly with respect to the work slide when the latter is in different postions.

The locating member is an arm 104 pivoted on a stud 105 which extends from one 55 end of a shaft 106 and is eccentric to the shaft. Said shaft is rotatably mounted in a bearing 107 on the upper end of the slide and protrudes therefrom at one end, whereon is secured an operating arm 108. The arm 104 is arranged to overhang the upper end of the base, and is rigidly connected to or integral with a second arm 109 carrying an adjustable screw stop 110 adapted to bear 60 on the adjacent upper surface of the work 90 slide.

Normally the operating arm 108 and locating arm 104 are in the position shown in Figure 1, where the axis of the pivot 105 is at the other side of the axis of the shaft, that is, the side away from the machine base. When the slide is at the lower end of its travel the locating arm is somewhat removed from the adjacent end of the base; but its distance away from the latter is less than twice the eccentricity of the pivot. It should be noted here that when the machine stops at the end of its cycle the work slide is always at the lower end of its travel. This is a condition which can always be depended on and is assured by the fact that the latch trip for shifting the driving belt is located to release the latch when the carriage is at or near its lowest point, and that the weight and friction of the reciprocating parts overcome any tendency which the driving pulley and shaft might have, by reason of their momentum, to start the carriage in the opposite direction.

Now, when the work piece is applied to the spindle, the operating arm of the locating device is brought from the position shown in Figure 1 to that shown in Figures 2 and 12, where it is arrested by a stop 111, and the locating lever 104 is thus shifted until its end bears on the adjacent surface 112 of the base. The screw stop 110 bears on the slide, before the operating arm has reached the stop 110, and the final movement of the latter arm acts, through the locating arm and stop, to move the work slide into a predetermined position. At the same time the former 8, which is constantly acted upon by

force holding its face 9 in contact with the abutment, is rolled into the predetermined position for setting of the work. It matters not what this precise position is, provided the gage is adjusted with reference to that position. What is accomplished by the locating means is the ability to place the slide in exact location, and in the same location, when each new work piece is applied. The capacity for adjustment of the stop 110 enables the location to be changed and graduation marks 113 on its head, coacting with a stationary index 114, enable the shifting of the slide from any fixed position to be exactly measured and its re-location at a known distance to be correctly effected.

The gage which cooperates with the locating means just described is a bar 115 (Figures 2, 13 and 14) mounted in a suitable holder and projecting at one end to enter a space between adjacent teeth of the work. The face 116 of the gage corresponds to a rack tooth face and makes contact with the adjacent face of tooth 117 of the work piece. The gage bar is secured by a set screw 118 in a holder 119 and the latter is pivoted by a pin 120 to a bracket 121, which, in turn, is adjustable toward and away from the work spindle on a guide 122. The guide, in turn, is angularly adjustable on a plate 123 which surrounds the work spindle and covers the end of the bearing sleeve thereof and is secured to a rigid part of the work slide.

To permit this angular adjustment of the guide 122, the latter is formed with a curved base portion 124 and curved slots 125, concentric with the work spindle. Clamp screws 126 passing through said slots in the base 124 and screwed into the plate 123 secure the guide in its various adjustments. Adjustments of the bracket 121 toward and away from the spindle are provided for to accommodate the gage to gear blanks of different diameters. A clamp screw 127, passing through the bracket and a slot 128 in the guide, secures these adjustments. A spring 129 stretched between abutments on the bracket and on the gage holder, respectively, normally holds the gage out of contact with the work piece and in the position shown by dotted lines in Figure 14.

When the gage is to be used, it is swung forward into a space of the work piece and may be made fast by tightening the pivot 120, the latter being a screw mounted in a well known manner to permit it to be tightened or loosened so as to clamp or release the part which turns about it. Thereafter the work piece is secured to the spindle by tightening the holding nut 130.

By adjusting the position of the gage angularly about the work spindle, the work piece may be adjusted to control the amount of material to be removed. In addition, a

fine and delicate adjustment may be given by turning the stop 110 while the gage is made fast to the work slide and the work piece is free to turn on its spindle. Such adjustment of the stop shifts the work slide and causes the former and the work spindle to be rotated relatively to the work piece, the latter being then held back by the gage. The setting of the gage is made with reference to work pieces having the maximum amount of material to be removed, and is preferably such that when such a work piece is applied to the spindle as described a light cut will be taken in the first pass over the grinding wheel.

The range of movement to be given to the former abutment for feeding the work between successive cuts, as previously described, is determined with respect to the same work piece; that is, one having the maximum amount of surplus stock to be removed. Then the back stop 32, to which the feed nut 26 is brought back after the completion of each gear, is set so that the abutment 11 will be brought into the proper relation to the former and to the gage to cause this light cut to be taken in such a work piece in the first pass. Then the amounts of rise of the several segments or lobes of the secondary work feeding cam 73 are determined according to the amount of stock to be removed from such a work piece in order to bring it to a final finished size. That is, the sum of the feeding steps given by the successive segments of the cam will be great enough to bring the former abutment to the point at which the tooth being ground will have the final thickness. It will be noted from Figure 2 that the face of the tooth on the work piece which bears on the gage face 116 is opposite to that face of the tooth which is acted on by the grinding wheel. Hence, a work piece on which the teeth are of less than maximum thickness will, when set as just described with reference to the gage, be more distant from the grinding wheel when the first pass takes place, than one of the greatest thickness.

It is part of my invention to enable work pieces having teeth of less than maximum thickness to be brought at once into grinding relation without changing the setting of the gage or of the locating means, and without affecting the timing mechanism, as by so doing it frequently happens that the time taken for a whole series of cuts, or even two or more series, on the work may be saved. To accomplish this end it is necessary that the secondary work feeding cam be rotatable independently of the timing mechanism, and that the work driving means should be disconnectable from the timing mechanism, so that the work may be brought into contact with the grinding

wheel before the timing mechanism begins to function. It is also necessary as a safety measure to be able to stop the machine at any time, and to re-start it, all without affecting the timing mechanism.

To serve these purposes, that part of the connection from the work driving mechanism to the timing mechanism which I have heretofore described as a bell crank lever having two arms 79 and 80, is made of two separate parts, both pivoted on the same fixed stud 131, as shown further in Figure 6. The arm 80 is provided with a lug 132 which overlaps arm 79, whereby the motion of the work driving mechanism is positively transmitted to the pawl 77 in the driving movement of the latter. Associated rigidly with arm 80 is an arm 133, and a spring 134 is wrapped around the hub of the lever 80-133 and engaged at its ends with the arms 79 and 133 so as to cause arm 80 to follow arm 79 on the return stroke but permit its being restrained by superior force from so following. Arm 133 has a latch shoulder 135 on the upper side of its outer end.

A lever 136 is mounted on a pivot 137 and has a lug 138 provided with a latch shoulder 139 on its under side adapted to overlie and interlock with the shoulder 135 as shown by dotted lines in Figure 1. A stud 140 is carried by said lever 136 and bears against the collar 96 on the belt shipper rod 94.

With the movements of the work driving mechanism the arm 133 oscillates between the full line position and the dotted line position shown in Figures 1 and 5, the associated arms 80 and 79 being also oscillated through the same range of movement. In the lowermost position of arm 133, but in no other position thereof, its locking shoulder 135 may be passed over by the lug 138 of lever 136. Said arm is in its lowermost position at the moment when the stop mechanism is tripped at the end of the grinding cycle, by the release of the belt shipper rod, as previously described; and at that time the collar 96 on the shipper rod 94 throws the lever 136 to the dotted line position, its lug then overlying the end of arm 133 and the shoulders 135 and 139 becoming interlocked. Any movement of the work driving mechanism which now takes place will have no effect on the timing mechanism.

This is the condition which exists whenever a new work piece is applied to the machine. When the piece has been gaged and set as described, the operator sets the machine in motion by pulling the shipper rod to the right in Figure 1 by means of the head 98. If the work does not come into contact with the grinding wheel in the first pass, the operator turns the secondary feed

cam 73 by means of the hand operated shaft 69 to give the first step to the work feeding mechanism. If in the next pass no grinding effect occurs, the operator feeds the work another step in the same way and continues to do so until grinding does begin. Then when the lever arm 79 takes its next upward step and arm 133 is depressed far enough to clear the shoulder 139, the operator moves the holding lever 136 out of the way of said arm and the connection is again made between the work driving mechanism and the timing mechanism. It is to be understood that the operator completes this connection as soon as the test carried out as above described shows that the work is far enough advanced to be ground. It may be on the first pass over the grinding wheel or after the feed mechanism has been advanced one, two, or even more of its steps. In case the teeth of the work piece should be considerably thinner than the maximum, much time is saved in grinding the piece to finished size because all of the preliminary motions required with a gear having teeth of maximum thickness are skipped.

The pawl and ratchet drive between the gear wheels 66 and 67 permits the feed mechanism to be advanced by hand in this way and enables it to be automatically connected with the timing mechanism as soon as the latter is put in operation. No particular care is needed on the part of the operator in turning the feed cam by hand, provided he completes each step of the feed and carries the high part of the cam segment past the rack bar. If he carries it a little too far no harm is done because of the subsequent dwell in the cam surface and the fact that the pawl, when advanced by the timing mechanism, will pick up the cam and advance it the remainder of the next partial rotation.

For stopping the machine in an emergency, I have provided a lever 141 pivoted to the frame at 142 and having a projection 143 adapted to engage a trigger 144. The trigger is pivoted on a stud 145 and has a finger 146 overlying an extension 147 on the latch 100. When the machine is running, the lever 141 occupies the position shown in Figure 1, but in order to stop the machine instantly in emergency this lever is raised to the position shown in Figure 5, where its projection 143 engages trigger 144 and disengages the latch 100 from the belt shipper rod 94. It is important at such times that the timing mechanism should not be disconnected from the work driving mechanism, because if, upon re-starting the machine, the operator should not thereafter immediately disengage lever 136 from the disabling arm 133 of the timing mechanism drive, the correct relation of the timing mechanism to the work driving mechanism would be destroyed; although the work driving mecha-

nism would roll the work past the grinding wheel, and index it after each pass, the timing mechanism would remain inoperative and no further feeding movements would be given to the work. Therefore, I mount the lever 136 in such a way that when it is thrown over by the belt shipper rod in the course of an emergency stop it will not interlock with the arm 133.

10 The pivot 137 of this lever is carried by a link 148 which is hung from a pivot 149 on the machine frame. The pivot 137 is connected by a link rod 150 to the lever 141 at the point 151. The lengths and positions 15 of these parts, namely, links 148 and 150 and pivots 149, 137, 142 and 151, are all so arranged that, when the emergency stop lever is raised to release the belt shipper, the pivot 137 is moved laterally, and slightly 20 downward. The lever 136 being then turned about this displaced pivot point by movement of the belt shipper, its lug 138 moves in a lowered path in which it is obstructed by the end of arm 133, even when the latter 25 is in its lowermost position, and will not pass over and lock such arm. When the emergency stop lever 141 is released it will drop back nearly to normal position. The machine may then be started again by 30 swinging the locking lever 136 to its normal position (that shown by full lines in Figure 1), where it tends to stay until displaced in either of the ways just described, or manually.

35 It may be noted that when the emergency stop lever 141 is in its normal or lowered position it rests against a stop 152 and in that position forms, with the link 150, a toggle linkage which holds the pivot 137 40 immovable by any force which may be applied thereto through the locking lever 136. In its turn the locking lever may be restrained in its normal or inoperative position by a suitably arranged spring or other 45 yielding withholding means which will prevent accidental interlocking engagement with the disabling arm 133 while permitting engagement therewith under superior force exerted by the shipper rod 97 when the lock 50 100 for said shipper rod is tripped.

By virtue of the locating means for the carriage, the gage for the work piece, which is adjustably fixed to the carriage, and the means for disconnecting the timing and feeding mechanisms from the work driving mechanism, it is possible to mount work pieces on the machine in such position that the subsequent automatic operation of the machine will remove the amount of stock 55 required to bring the pieces to final finished form and dimensions; and to set up the work piece thus and bring it into contact with the cutting tool with a minimum expenditure of time. This time saving in the performance of the cutting action is of particular 60 65

value in view of the fact that the conditions of this character of work, in the automatic operation of the machine, require all of the teeth of the work piece to be carried past the cutting tool before any increment of feed 70 movement is given to the work.

It is apparent, of course, that the setting of the work and operation of the machine as heretofore described results in the finishing of the gear teeth on one side only, and 75 that thereafter the work piece must be removed reversed and replaced on the spindle, and adjusted as before, in order to finish the opposite faces of the teeth. Equal proportions or different proportions of the total 80 amount of material to be cut away in bringing the teeth to finished dimensions may be removed from each side, but for various reasons it is considered preferably in practice to set up the work for the first grinding so 85 that less than one-half of the total amount of material will be removed then, leaving the greater amount to be removed when finishing the second side of the teeth. That is, in the first cycle, the teeth are ground on 90 one side deeply enough to bring them to true form and then a little more material is cut away; in other words, to grind away a little more than enough to "clean up" all of the teeth on one side, leaving to the cycle of 95 operation performed on the other side the task of bringing the teeth to final finished dimensions as well as true form. This is only a preferred practice, however, and is 100

The practical necessity of the locating device which I have previously described is due to the fact that the work carriage cannot be depended upon to stop always in exactly the same position when the machine is 105 stopped, although the stopping place may be nearly the same on all occasions. The particular locating device described is not the only means which may be used for the same purpose, but may be considered as a 110 typical means and as representing generically any and all forms of such means.

An alternative device for the purpose, which is considered as embraced within the generic definition of such means, consists 115 in provisions for moving the operating or impelling cam 13 to a given position when setting up the work, for this will also bring the work carriage to a single given position. I may thus locate the cam by engaging it directly in various ways. One way is to insert a bar through a slot 155 in the part of the frame which surrounds the cam (see Figure 1), and into a hole 156 in the cam (see Figure 3) which comes within the range 120 of the slot when the machine stops. Then by moving such inserted bar until it brings up against one end of the slot a fixed locating point for the cam and consequently for 125 the carriage, is found. Another way of so 130

moving the cam as to obtain the same result consists in turning the shaft 53 manually by a wrench or equivalent device applied to the outer end of said shaft. As this shaft 5 is made fast to the sleeve 46 and the latter is geared to the sleeve 44, carrying the impelling cam 13 through the train consisting of the gears 49, 48 and pinion 50, rotation of the shaft will rotate the cam. The position 10 to which the cam is thus moved is determined by the stop pawl 85 and that one of the abutments 84 on the sleeve 46 which is adjacent to the pawl when the machine stops.

The characteristics of the timing mechanism 15 are such that when the machine stops at the end of its cycle, the pawl or dog 85 drops in the path of the abutments 84. Then, in accordance with the present invention, the lowest part of the cam, when in engagement with the roll 17 on lever 14, is slightly in advance of the engaging location of the nearest abutment 84 with the stop pawl 85. The machine naturally comes to rest when the lowest part of the cam is 20 beside this roll. The relation of the abutment and stop pawl is then substantially as indicated in Figure 15. The manual rotation which is now given to the shaft 53, in order to locate the carriage as just described, 25 turns the cam until abutment 84 is arrested by the stop pawl 85. This is an exactly determined location and it causes the carriage, in turn, to be placed in an exact location, and in the same location whenever a new work 30 piece is applied.

Although in the foregoing description I have referred to the work as a spur gear, it is to be understood that the same character of operations may be performed by machines having the same principles as hereinbefore described, upon specifically different but generally analogous articles, such as sprocket wheels, multi-lobed cams, or other articles having a number of peripheral projections, the faces of which are capable of being shaped by compound generating and cutting movements. Hence the term "gear", as used in this specification, unless otherwise modified by the context, is intended to include all such similar or analogous articles as well as the specific machine element known as a spur gear.

Evidently reversals and other modifications in the arrangement and structure of the parts of the machine may be made within the spirit of the invention, wherefore it is to be understood that I do not limit my claim for protection to the details of the machine here illustrated, and that the appended claims are to be construed as including such reversals and modifications within the range of their equivalents.

What I claim and desire to secure by Letters Patent is:

1. A generating machine of the character

set forth including a reciprocating carriage, a spindle rotatable on said carriage, means for rotating the spindle when the carriage is reciprocated, mechanism for giving increments of rotary feed movement to the spindle, timing mechanism for causing such increments of feed movement to take place in alternation with a series of reciprocating movements of the carriage, a locating means for placing the carriage in a definite position, and a gage mounted adjustably on the carriage and adapted to determine the position of a work piece on said spindle.

2. In a generating machine having a base, a carriage movable back and forth on said base, a work spindle rotatably mounted on the carriage, a former connected with the spindle, a complemental normally stationary abutment arranged to cooperate with said former in giving a rolling motion to the spindle when the carriage is so moved, an adjustable locating member arranged to cause placement of the carriage in a given location on the base, and a gage mounted on the carriage and arranged to make contact with a part of a work piece to cause placement of the work piece in a given angular relation to the former when the carriage is in such position.

3. A generating machine of the character set forth, comprising a base, a work carriage movable back and forth on said base, a work spindle rotatably mounted on said carriage, complemental elements connected to said spindle and base, respectively, and arranged to impart rolling motion to the spindle when the carriage is thus moved, mechanism for so moving said carriage, automatic mechanism for shifting one of said complemental elements, a timing mechanism constructed to cause alternate action of the carriage driving means and said automatic shifting mechanism, said last-named mechanism including a driving impeller positive in one direction only, and manually operable means for propelling the shifting mechanism independently of its automatic impeller.

4. In a gear generating machine having a former and an abutment, one of which is arranged to roll upon the other for giving rolling movement to a work piece, said abutment being movable independently of rolling action so as to give a feeding increment of rotation to the work piece, an automatic feeding mechanism for so moving said abutment including a driving part, a driven part and a propelling connection between said parts arranged to transmit motion from the driving part to the driven part and to permit independent movement in the same direction of the latter ahead of the former, and means for enabling the driven part to be driven independently by manual operation.

5. In a gear generating machine, automatic gear rolling mechanism including a

carriage, a spindle rotatably mounted on the carriage, a former connected with the spindle, and an abutment arranged to cause rotation of the former when the carriage is moved, driving mechanism for the carriage, said abutment being shiftable to change the angular position of the former and spindle independently of the carriage, automatic mechanism for so shifting the abutment, timing mechanism driven alternately by the carriage driving means and the abutment shifting mechanism, respectively, for causing each of the other mechanisms to become operative exclusively in alternation, and means for interrupting the connection between the carriage driving mechanism and the timing mechanism, whereby to permit a preliminary adjustment of the work.

6. A gear generating machine comprising a carriage, a rotatable work spindle mounted on said carriage, a former secured to the work spindle, an abutment cooperating with the former to oscillate the spindle when the carriage is moved back and forth, automatic work driving mechanism for moving the carriage, automatic abutment shifting mechanism for displacing the abutment to give a feeding movement to the work spindle, timing mechanism constructed and adapted to put said work driving mechanism in operation, at the same time disabling the abutment shifting mechanism, and to put said abutment shifting mechanism into operation at the same time disabling the work driving mechanism, means by which the work driving mechanism and the abutment shifting mechanism, in turn, drive said timing mechanism, means for disabling the drive from the work feeding mechanism to the timing mechanism, and means for manually shifting the abutment independently of the automatic mechanism for that purpose.

7. In a gear generating machine having a base, a back and forth moving work carriage, a spindle rotatably mounted on the carriage, a former secured to the spindle and a complementary abutment for rotating the spindle when the carriage is so moved, an adjustable locating member engageable with the carriage and base for placing the carriage in a given position on the base and shifting it by measured amounts, a work gage secured to the carriage adapted to contact with a work piece on the spindle and being adjustable angularly about the spindle, automatic mechanism for driving the carriage, automatic mechanism for shifting the abutment to feed the work, timing mechanism for putting each of the preceding mechanisms alternately into operative condition, at the same time putting the other of said mechanisms out of action, a disconnectable driving connection from the carriage operating mechanism to the timing mechanism, and a transmission connection in the abut-

ment shifting mechanism which is positive only in the feeding direction and is yieldable to permit advancement of the abutment beyond the mechanism for automatically shifting it.

8. In a generating machine of the character described, a base, a carriage movable back and forth on said base, a locating means for setting the carriage in a given position on the base near one end of its travel, said locating means comprising an arm, a shaft rotatably mounted on the carriage and having an eccentric stud on which said arm is pivoted, a second arm associated with the first-named arm and having a stop member so adapted to bear on the carriage when the first arm bears on an adjacent part of the base, and an operating arm secured to the shaft and operable to rotate the latter so as to bring the aforesaid arms into and out of operation.

9. In a generating machine of the character described, a base, a carriage movable back and forth on said base, and means for locating the carriage in a definite position on the base comprising connected arms, one of which is adapted to bear on a surface of the base and the other to bear on a surface of the carriage, and a movable mount for said arms operable to place them in and out of operative position.

10. In a generating machine of the character described, a base, a carriage movable on said base, and a carriage locating means comprising connected arms and a mount on which said arms are rotatably supported, said mount being shiftable to put said arms into a position where one of them is adapted to bear on the carriage and the other is adapted to bear on the base, one of said arms having an adjustable stop through which its aforesaid engagement is effected.

11. In a generating machine of the character set forth and including a base, a carriage movable thereon, and locating means for putting the carriage in a given position on the base and comprising associated arms mounted on one of the two members constituted by the base and carriage and adapted to bear on said members respectively, that part of one of the arms which engages with the adjacent member being adjustable relatively to the other arm, whereby to effect an adjustment in the positioning of the carriage.

12. In a machine of the character described having a carriage, a work spindle mounted on the carriage, a former connected to the work spindle and a relatively stationary abutment against which the former acts, a gage mounted on the carriage with provision for adjustment angularly about the axis of the spindle and mounted to coact with a peripheral projection of the work piece, and a mount for said gage constructed to

permit displacement of the gage out of the path taken by such projection when the work piece is rotated with the spindle.

13. In a generating machine, a carriage, a work spindle rotatably mounted on the carriage, a gage supporting bracket angularly adjustable on the carriage about the axis of the work spindle and a gage holder pivoted to said bracket with provision for swinging into and out of engagement with a peripheral projection of a work piece mounted on the spindle.

14. In a generating machine of the character described a carriage, a work spindle rotatably mounted on the carriage, a guide secured to the carriage with provision for angular adjustment about the axis of the spindle, a gage holding bracket secured to said guide with provision for adjustment 20 toward and away from the spindle, a gage holder pivoted to the bracket, and a work gage secured to the holder, said holder being movable about a pivot to put the gage into and out of position for engaging a 25 peripheral projection of the work piece.

15. In a generating machine having a work-controlling former and an abutment cooperating with said former, means for displacing the abutment to give an angular feeding movement through the former to the work, said abutment-displacing means including a screw and a nut, mechanism for rotating the nut in one direction to displace the screw, a back stop, and a cooperating abutment on the nut arranged to establish one of the limits of the shifting movement of the abutment.

16. In a generating machine having a work-controlling former and an abutment cooperating with said former, means for displacing the abutment to give an angular feeding movement through the former to the work, said abutment-displacing means including a screw and a nut, mechanism for 40 rotating the nut in one direction to displace the screw, a back stop, and a cooperating abutment on the nut arranged to establish one of the limits of the shifting movement of the abutment, said back stop being adjustable to vary the location of such limit.

17. A gear generating machine including a work spindle, a movable carriage on which said work spindle is rotatably mounted, a former connected to the spindle, a relatively stationary abutment cooperating with the former for giving a rolling motion thereto and to the spindle when the carriage is moved, the abutment being shiftable in a manner to cause angular movement of the former, whereby to give feed movements to the work, an intermittently movable feed mechanism for said abutment adapted to shift the latter step by step, and an adjustable limit stop for limiting the displacement of the abutment in one direction.

18. A gear generating machine including a work spindle, a movable carriage on which said work spindle is rotatably mounted, a former connected to the spindle, a relatively stationary abutment cooperating with the former for giving a rolling motion thereto and to the spindle when the carriage is moved, the abutment being shiftable in a manner to cause angular movement of the former, whereby to give feed movements to the work, an intermittently movable feed mechanism for said abutment adapted to shift the latter step by step, said feed mechanism being reversible in part to place the abutment at a predetermined starting position, and a limit stop determining said starting position.

19. The method of setting up a gear or the like for finishing in a machine which has a carriage, a cutting tool, a work spindle, a former, and a former abutment, all cooperatively arranged to cause rolling movement of a projection of the work piece over the face of the cutting tool when the carriage is moved back and forth, such method of setting up consisting in placing the carriage at a given point and while the carriage is so placed setting the work piece on the spindle in a given angular relation to the former.

20. The method of setting up a gear or the like for finishing in a machine which has a carriage, a cutting tool, a work spindle, a former, and a former abutment, all cooperatively arranged to cause rolling movement of a projection of the work piece over the face of the cutting tool when the carriage is moved back and forth, such method of setting up consisting in placing the carriage at a given point and while the carriage is so placed setting the work piece on the spindle in a given angular relation to the former, then making a test traverse of the work over the cutting tool, and finally shifting the abutment in a direction to give angular movement to the former independently of the carriage travel until the cutting tool is caused to act on the work in the next subsequent pass thereto.

21. The method of setting up work in a finishing machine having a movable carriage, a cutting tool, a work spindle rotatably mounted on the carriage, a former connected to the spindle, a relatively stationary abutment cooperating with the former, all arranged and cooperating to cause rolling movement of the spindle and work piece thereon relatively to the cutting tool when the carriage is moved, said machine also having mechanism for shifting the abutment in a manner to give angular feed movement to the work through the former and spindle and having also a work gage angularly adjustable with respect to the spindle, and a locating device for determining the location

of the carriage at a fixed point in its travel, said method consisting in locating the gage in such angular relation to the former that when a work piece having a maximum amount of stock to be removed in finishing is placed on the spindle in locating engagement with the gage, the carriage then being in a given position, such work piece will be correctly related to the cutting tool to be 10 acted on by the latter when rolled past it; then placing similar work pieces, but having less stock to be removed, on the spindle with the same setting of the gage and carriage, making a test pass of the work over 15 the cutting tool, and thereafter manually displacing the abutment and making a further test pass until the work is brought to the adjustment where it is acted on by the cutting tool.

20 22. In a gear generating machine having a carriage, a work spindle, a former and an abutment combined with a grinding wheel and arranged to cause such combined movement of a work piece fixed to the spindle, when the carriage is moved, that a tooth face of the work piece rolls over the face of the grinding wheel, a step by step feed mechanism for shifting the abutment so as to advance the work relatively to the grinding wheel, an automatic driver for said feed mechanism, a power transmitter between said driver and mechanism which is positive only in the forward direction, and a manually operated driver for said feed mechanism applied thereto in advance of said power transmitter.

23. In a generating machine of the character set forth, a work driving mechanism, a timing mechanism, a transmission mechanism from said work driving mechanism to the timing mechanism and including a transmission member which is positive in one direction only and a yieldable connection through which movement in the opposite direction is transmitted, there being a detent element on the power-receiving part of said transmission mechanism, combined with an automatic means for stopping the machine, and a locking member operable by said stopping means and arranged to interlock with said detent element to prevent actuation of the timing mechanism when the machine is again started.

55 24. In a machine of the character described the combination, with a work driving mechanism, of a transmission member driven thereby and including a driver, a follower and a spring, which driver and follower are arranged to transmit motion in one direction only and the spring is connected to them in a manner to transmit motion in the opposite direction but to yield when the follower is arrested, a detent connected to 60 the follower and a lock operable to withhold

said detent when the follower is approximately at the end of the movement given by the positive action of the driver.

25. In a machine of the character described the combination with a work driving mechanism, of a transmission member driven thereby and including a driver, a follower and a spring, which driver and follower are arranged to transmit motion in one direction only and the spring is connected to them in a manner to transmit motion in the opposite direction but to yield when the follower is arrested, a detent connected to the follower, a lock operable to withhold 70 said detent when the follower is approximately at the end of the movement given by the positive action of the driver, said lock being combined with a movable belt shipper, a lock for holding said shipper in the position which causes the machine to run, and an automatic trip for causing said shipper to stop the machine at the end of the cycle, the lock and shipper being so arranged that the movement of the shipper to stop the machine causes arresting engagement of the lock with 80 said detent.

26. In a gear generating machine, an automatic work driving mechanism, an automatic work feeding mechanism, an automatic timing mechanism constructed to cause alternate operation of each of the preceding mechanisms in turn and with simultaneous intermission of the other mechanism, an automatic stopping mechanism for stopping the machine, a trip operated by the timing mechanism for causing actuation of said stopping mechanism, driving connections from the work-driving mechanism to the timing mechanism including complementary transmitting and following members which are positive in one direction only and a spring which is arranged to transmit motion in the opposite direction, a detent associated with said following member, and a lock arranged to engage said detent and prevent movement of the following member through said spring when the machine stopping means is automatically actuated.

27. In a gear generating machine, an automatic work driving mechanism, an automatic work feeding mechanism, an automatic timing mechanism constructed to cause alternate operation of each of the preceding mechanisms in turn and in simultaneous intermission of the other mechanism, an automatic stopping mechanism for stopping the machine, a trip operated by the timing mechanism for causing actuation of said stopping mechanism, driving connections from the work-driving mechanism to the timing mechanism including complementary transmitting and following members which are positive in one direction only 110

and a spring which is arranged to transmit motion in the opposite direction, a detent associated with said following member, and a lock arranged to engage said detent and prevent movement of the following member through said spring when the machine stopping means is automatically tripped; the aforesaid combination being further combined with manual means for tripping the stopping means, and connections between said manual means and lock constructed to place said lock in a position where it can not arrest said detent.

28. In a machine of the character described, the combination of a transmission mechanism having impelling and following members engaged to transmit thrust positively in one direction but being separable in the other direction, a spring applied to said members normally holding them together and transmitting motion in said other direction, a detent arm connected with said following member and movable simultaneously therewith, a pivoted locking member adapted to overlap and interlock with said arm when the latter is at one extreme of its movement, a machine-stopping means including a laterally movable member engaged with said pivoted locking member in a manner to swing the same into position for interlocking with the detent arm when said member is displaced, a shiftable fulcrum for said locking member, and a manually operated tripping means for said machine-stopping means, connected with said fulcrum to displace the latter whenever the former is operated to stop the machine, said fulcrum being guided to move in a path such that upon the locking member being then displaced by the machine-stopping means it is obstructed by the detent arm and prevented from interlocking therewith.

29. In a generating machine, a carriage, a work spindle rotatably mounted on the carriage, and a gage mounted on the carriage with provision for placement in position to locate a work piece angularly on said spindle, and to be withdrawn from its locating engagement with the work piece.

30. In a generating machine, a carriage, a work spindle rotatably mounted on said carriage, means for giving a generating motion to a work piece mounted on said spindle, which motion is compounded of displacement of the carriage and rotation of the spindle, combined with a gage mounted on the carriage and adapted to obstruct a peripheral projection on the work piece, and provisions for withdrawing the gage from such relation to said projection.

31. In a generating machine, a carriage, a work spindle rotatably mounted on the carriage, and a gage mounted on the carriage with provision for placement in posi-

tion to locate a work piece angularly on said spindle, and to be withdrawn from its locating engagement with the work piece; in combination with means for locating the carriage in a given position. 70

32. A generating machine of the character set forth comprising a base, a carrier reciprocatable thereon, a work spindle, a former connected with said spindle, an abutment cooperative with said former, a rotatable cutting tool arranged to act on a work piece mounted on said spindle; said elements being cooperatively arranged and organized to effect relative rolling motions between the work piece and the tool; means for locating the carriage in a definite position with respect to the base in setting up the work, and a gage for the work piece arranged to determine the angular relation between said piece and the former when the carriage is so located. 80

33. A generating machine of the character set forth comprising a base, a carriage reciprocatable thereon, a work spindle, a former connected with said spindle, an abutment cooperative with said former, a rotatable cutting tool arranged to act on a work piece mounted on said spindle; said elements being cooperatively arranged and organized to effect relative rolling motions between the work piece and the tool; means for locating the carriage in a definite position with respect to the base in setting up the work, and a gage mounted with provision for angular adjustment about the axis of the work spindle relatively to the former and having an element adapted to be placed in gaging contact with the work piece when the carriage is so located. 95

34. In a generating machine of the character set forth, having a carriage, a work spindle, a cutting tool, and mechanism for effecting translatable movements of said carriage and rolling movements between the work spindle and cutting tool, work setting means comprising a gage for the work piece and a locating device for the carriage, cooperatively arranged to determine the angular relation of the work piece to the tool when the carriage is in a given position. 105

35. In a generating machine of the character set forth, having a carriage, a work spindle, a cutting tool, and mechanism for effecting translatable movements of said carriage and rolling movements between the work spindle and cutting tool, work setting means comprising a gage angularly adjustable about the axis of the work spindle and shiftable into and out of gaging relation to the work piece, and a locating device for the carriage. 120

36. A generating machine of the character set forth comprising a base, a carriage, a work spindle, a generative cutting tool, 130

means for causing rolling generative movement to take place between said work spindle and cutting tool, with movement of the carriage upon the base, and means for setting up a work piece on the work spindle in operative relation to the cutting tool, said last named means consisting in provisions for locating the carriage at a given point, and provisions for locating the work piece on the spindle in a given angular relation when the carriage is so located.

37. A generating machine of the character set forth comprising a base, a carriage,

a cutting tool, a work spindle, a former, and a former abutment, all cooperatively arranged to cause rolling movement between a work piece applied to said work spindle and the cutting tool when the carriage is moved back and forth, and means for setting up the work piece consisting of provision for locating the work piece in a given angular relation to said former when the carriage is in a given location with respect to the base.

In testimony whereof I have affixed my signature.

EDWIN R. FELLOWS.
